Y. T. GOODWIN

STATUETTE

Filed March 5, 1923

*Inventor:
Yuba T. Goodwin,
by Walter E. Lombard, Atty.*

Patented July 24, 1923.

Des. 62,721

UNITED STATES PATENT OFFICE.

YUBA T. GOODWIN, OF EAST DEDHAM, MASSACHUSETTS.

DESIGN FOR A STATUETTE.

Application filed March 5, 1923. Serial No. 5,365. Term of patent 3½ years.

To all whom it may concern:

Be it known that I, YUBA T. GOODWIN, a citizen of the United States, residing at East Dedham, in the county of Norfolk and State of Massachusetts, have invented a new, original, and ornamental Design for Statuette, of which the following is a specification, reference being had to the accompanying drawing, forming part thereof.

The figure is a perspective view of a statuette, showing my new design.

I claim:

The ornamental design for a statuette, as shown.

YUBA T. GOODWIN.

Witnesses:

WALTER E. LOMBARD,
NATHAN C. LOMBARD.
